DESIGN FOR A WATCH BAND CLIP

George M. Ellesson, Bridal Veil, Oreg., assignor
to G. M. Ellesson Company, Chicago, Ill., a cor-
poration of Illinois

Application March 17, 1948, Serial No. 145,179

Term of patent 14 years

(Cl. D45—4)

To all whom it may concern:

Be it known that I, George M. Ellesson, a citizen of the United States, residing at Bridal Veil, in the county of Multnomah and State of Oregon, have invented a new, original, and ornamental Design for a Watch Band Clip, of which the following is a specification, reference being had to the accompanying drawing, forming a part thereof.

In the drawing—

Fig. 1 is a plan view of a watch band clip, showing my new design.

Fig. 2 is a side view in elevation of the watch band clip shown in Fig. 1.

Fig. 3 is an end view of the watch band clip, the view being taken looking toward the left side of the clip shown in Fig. 1.

Fig. 4 is an end view of the watch band clip, the view being taken looking toward the right side of the clip shown in Fig. 1.

I claim:

The ornamental design for a watch band clip, substantially as shown.

GEORGE M. ELLESSON.
